CENTRIFUGAL FAN WITH WAVE TRAP AND CUT-OFF

William J. Caldwell, Independence, Mo.

Application June 27, 1951, Serial No. 233,751

2 Claims. (Cl. 230—114)

This invention relates to centrifugal fans and in particular to centrifugal fans of the character disclosed in my prior Patent No. 2,335,734, issued November 30, 1943.

According to the centrifugal fan disclosed in my said prior patent, a fixed flexible gate is provided in the discharge nozzle, which gate functions as a cut-off to regulate the volume of air discharged through the nozzle by the action of the fan blades. In connection with such a fan assembly, designed to compress air to 3 inches, for example, the passage of the fan blades past this cut-off gate has been found to give rise to a buzzing noise due to the "slapping" of the air stream against the gate and the sudden arresting of the air flow by the impingement of the velocity of air against the cut-off gate. This buzzing noise is a characteristic of pressure type fans and is attended with the creation of compression sound waves, which travel both along the discharged air stream as well as back through the fan inlet, due to the velocity of these waves being in excess of the velocity of the normal air flow through the fan assembly.

It is an object of the invention to provide an improved centrifugal fan assembly in which the above stated disadvantages of a fixed cut-off are avoided.

It is another object of the invention to provide a centrifugal fan having an improved cut-off which is quiet in operation.

These, and further objects and advantages of the invention will appear clear from consideration of the following description with reference to the drawings in which:

Fig. I is an end view of a fan assembly having a perforated and slotted cylindrical cut-off silencer according to the invention,

Fig. II is a section on the line II—II of Fig. I,

Fig. III is an exploded perspective view of the cut-off cylinder and its adjustable mounting means, and

Fig. IV is a cross-section of a fan housing with an alternative cut-off silencer in accordance with the invention.

The centrifugal fan illustrated in the drawings may be of the same general construction as is disclosed in the said prior Patent No. 2,335,734 but, referring first to Figs. I to III, includes an improved cut-off silencer device in the form of a cylinder 10 mounted in the fan discharge nozzle 12 of the fan casing 14 in proximity to the outer periphery of the fan blade assembly 16, the rotary shaft of which is indicated at 18.

The cylinder 10 is perforated throughout its surface area except for the existence of an axially extending slot 20, which extends the full length of the cylinder and is disposed to face downstream with respect to the discharge of the pressure air through the nozzle 12, as shown in Fig. II.

This cylindrical cut-off device possesses distinct advantages over the fixed gate structure of my prior patent. First, the cylinder 10 presents a blunt impact surface, much like the leading edge of an aerofoil, and permits the impinged air stream to seek its best streamline char-

acteristic. Second, and of considerable importance, is the fact that the compression waves resulting from the striking of the air stream from the fan blade assembly against the perforated cylinder surface are not reflected from this surface, as in the case of a solid surface, but follow the pattern of airflow against a conventional perforated acoustic ceiling, with these sound waves being admitted through the cylinder perforations to pass into the cylinder. Here, the presence of the axial slot 20 has significance. The existence of this slot breaks up the presence of a continuous reflecting surface within the cylinder and thereby eliminates the possibility of the admitted air finding a focal point within the cylinder from which reflection of these sound waves can take place.

These pressure type centrifugal fans exhibit considerable sensitivity to the position of the cut-off device if the best air delivery performance is to be obtained. To provide for the obtaining of adjustment as to this I arrange for the cut-off cylinder 10 to be adjusted in position not only with respect to the distance of the cylinder from the periphery of the fan blade assembly in a radial direction but also transversely with respect to the discharge nozzle 12.

These adjustments are possible by providing oval holes 22 in the opposed walls of the casing 14, through which holes spindle-like extensions 24 at the cylinder ends extend to the outside of the casing walls and receive thereover, in turn, a sealing disc 26, a washer 28, and a nut 30. The disc 26 has a central opening through which said extension 24 passes with a sliding fit. With this arrangement it is readily possible to adjust the location of the cylinder 10, as above stated, simply by loosening the nuts 30 and shifting the cylinder within the limits of the holes 22, with respect to which the discs 26 provide an effective seal in the tightened condition of the nuts 30.

In Fig. IV I have shown a modified construction of cut-off silencer involving three cylinders 32, 34, 36 arranged in nested radially spaced eccentric relationship, as shown, with each cylinder presenting a perforated surface to the air flow from the fan and the size of the perforations varying decreasingly in size from the outermost cylinder to the innermost one. Thus, the perforations in cylinder 32 may be $1/8$ " diameter, in cylinder 34, $3/16$ ", and in cylinder 36, $1/16$ " diameter. This triple cylinder assembly is mounted within the fan housing outlet duct or nozzle 38 in close proximity to the discharge side of the fan, shown in outline at 40, and may be supported therein upon axially spaced brackets, one of which is shown at 42, whereas the two inner cylinders 34 and 36 may be complete cylinders, as shown. The outer cylinder 32 may be constituted by a perforated sheet formed to the desired cylindrical form and welded to the cylinder 34 along its longitudinal edges, as indicated at 44.

Having thus described my invention what I claim as new and desire to protect by Letters Patent is:

1. In a centrifugal fan having a casing with a discharge nozzle and a fan assembly rotatable in said casing to discharge pressure air through said nozzle, a cut-off device in said nozzle for regulating the discharge therethrough, said cut-off device comprising an elongated generally cylindrical member mounted to extend across said discharge nozzle in proximity to the outer periphery of said fan assembly, said elongated member having an upstream perforated surface presented to the pressure air discharged from said fan assembly, the down-stream surface of said member defining an enlarged opening extending longitudinally along the axis of said elongated member and transversely of the stream of pressure air.

2. The invention as defined in claim 1, means adjustably mounting said cut-off cylinder in said

3

means permitting the cylinder to be adjusted radially with respect to the fan assembly and transversely with respect to said discharge nozzle.
